UNITED STATES PATENT OFFICE.

FRANCIS M. VAN ETEN, OF NEW YORK, N. Y.

DESIGN FOR A SOUVENIR-SPOON.

SPECIFICATION forming part of Design No. 31,117, dated July 4, 1899.

Application filed June 3, 1899. Serial No. 719,308. Term of patent 3½ years.

To all whom it may concern:

Be it known that I, FRANCIS M. VAN ETEN, a citizen of the United States, residing at New York, in the county of New York and State of New York, have invented and produced a new and original Design for a Souvenir-Spoon; and I do declare the following to be a full, clear, and exact description of the same, reference being had to the accompanying drawings, forming a part thereof.

Figure 1 is a view of the front of the spoon, showing the Christmas design; and Fig. 2 is a view of the back of the spoon, showing the New-Year design.

As shown in the drawings, the leading or material feature of my design consists in the scrolls, moon, fireplace, stocking, and tree on the front of the handle and Santa Claus

in a sleigh drawn by a deer in the bowl of the spoon, and on the back of the handle three bells, Father Time, Infant New Year, with holly-leaves, and scrolls.

It is immaterial in what way the design is represented on the spoon, whether raised, engraved, or otherwise.

Having described my invention, what I claim as new, and desire to secure by Letters Patent, is—

The design for a souvenir-spoon, as shown and described.

In testimony whereof I affix my signature this 25th day of May, 1899.

FRANCIS M. VAN ETEN.

In presence of—

HERBERT R. SNYDER,
C. H. CHILDS.
